ILLUMINATED TELESCOPE FOR INSTRUMENTS

Filed May 4, 1931

Inventor:
WILLIAM J. CAMERON.

E. Rindfuss Atty.

UNITED STATES PATENT OFFICE

WILLIAM J. CAMERON, OF CHICAGO, ILLINOIS
ILLUMINATED TELESCOPE FOR INSTRUMENTS

Application filed May 4, 1931. Serial No. 534,891.

My present invention relates to surgical instruments and more particularly to instruments of the speculum type which are adapted for insertion into cavities for the purpose of inspecting interior areas and for operation thereon. Specifically my present structure relates to means for illuminating the area under inspection and for magnifying said area by means of an adjustable telescope 10 through which the area is viewed. The structure is used in connection with a handle upon which the instrument is removably mounted, and means are provided in the handle for raising a lamp substantial into alinement 15 with the axis of the instrument and for lowering the lamp slightly to clear the field for operation or treatment. In this connection I have also provided a telescope that is removably mounted on the handle, and other means 20 are provided for adjusting the telescope so as to focus it upon the area for the examination.

One of the objects of my invention is to provide an instrument of the character above mentioned that is simple in construction and may be readily manipulated by the operator when performing the examination, operation or treatment. The device is made of simple parts that may be readily disassembled for the 30 purpose of sterilization and may be entirely knocked-down for storage in a relatively small space.

The handle is coordinated with the speculum in such manner that instruments of different character may be readily mounted on the handle. The device is dependable and efficient in operation, and the telescope and lamps are arranged in such manner that the former may be retracted and the latter may 40 be moved out of alinement with the tool so that the surgeon may insert instruments for the purpose of operation or treatment.

I prefer to carry out my invention, and to thereby accomplish the numerous objects 45 thereof, in substantially the manner herein-

after fully described and as more particularly pointed out in the claims. Reference will now be made to the accompanying drawing that forms a part of this specification.

In the drawing:—

Figure 1 is a vertical side elevation of my invention showing the parts in position for use in making examinations.

Figure 2 is a horizontal section on line 2—2 of Figure 1 showing the handle, the lamp and the telescope in top view.

Figure 3 is a view at right angle to Figure 1 looking into the instrument and with the telescope and lamp moved to positions to clear the field for operation or treatment.

Figure 4 is a detail, partly in section, showing the manner of movably mounting the telescope.

The drawing is more or less schematic for the purpose of illustrating a typical or preferred form in which my invention may be made, and in this drawing similar reference characters are used to designate like parts wherever they appear throughout the different views.

Referring more particularly to Figure 1, the structure there shown comprises a hollow tubular handle 5 having electric terminal connectors 6 at its lower end, and in its upper portion there is a longitudinally movable body consisting of a head 7 having therein a small electric socket 8 to receive a miniature electric lamp or bulb 9. As will be seen in Figure 1, the lamp is of inverted L-shape or angle-shape and is provided with a lens 10 for increasing or magnifying the light rays emanating from it.

The head 7 of the movable body is connected by a reduced neck portion 11 to a slide block 12, and the conductors from the socket 8 pass through the head, the neck, and the block and extend down in the hollow handle 5 to the terminal connectors 6. The side of the handle is provided with a longitudinal slot (not shown) and a sliding thumb plate 90

13 for exteriorly operating the movable body covers this slot and is connected by a pin or screw 14 with the block 12. With this construction, the operator may move the slide 13 up or down thereby elevating or retracting the lamp or bulb 9 to the location desired. In its uppermost position the lamp or bulb 9 is substantially in alignment with the axis of the speculum so as to concentrate the rays of light towards and through the open end of the instrument, and in a lowered position the lamp will be retracted away from the axis of the instrument but will continue to illuminate the area under inspection while at the same time permitting the surgeon to insert an instrument for operation or treatment.

The instrument shown in the drawing is preferably an ear or nose speculum that consists of a hollow tapered or cone-shaped portion 15 having an annular rib 16 at its base that acts as a stop, and beyond the rib there is a concentric flange or sleeve portion 17 of cylindrical formation. This speculum is removably mounted in a holder that is removably carried on the upper portion of the handle 5. This holder comprises a split band 18 the ends of which are formed into ears 19 which are drawn together by a wedge block 20 that is operated by a short lever 21.

The band is of sufficient dimensions to readily receive the flange or sleeve portion 17 of the speculum, and when the lever 21 is moved the band will become constricted around the sleeve 17 and will firmly hold the speculum in position.

The lower portion of the band flares away from the speculum and is provided with a tubular socket portion 22, that is preferably open at both top and bottom and is disposed laterally to the axis of the speculum and the clamping band as can be seen in Figure 1. This permits this socket portion 22 to be inserted over the lamp or bulb and the end of the handle so as to be carried upon the upper end thereof.

The telescope is also removably carried upon the upper portion of the handle by means of a bracket 23 that extends radially or laterally from the handle 5 and has oppositely curved spring clip arms 24 that frictionally engage the support. In the drawing the spring arms have been shown as partly surrounding the tubular socket portion 22 of the speculum mounting structure, but it will be understood the arms may engage an upper portion or adjacent portion of the handle 5. This could be done by elongating the interior body member and by placing the slot and the outer slide 13 lower on the handle. The outer portion of the bracket 23 is formed into a somewhat cylindrical boss 25 having a flat disk-like flange 26 upon its upper end. The boss is provided with a bore 27 that has a reduced upper portion 28 to provide a shoulder 29.

The viewing device comprises a pair of telescopically arranged tubes 30, carrying the usual lenses for magnification, which tubes are adapted to be moved relative to each other for the purpose of focusing the lenses upon the area illuminated by the lamp. The telescope is mounted on the bracket 23 so that it may be swung laterally, as shown in Figures 2 and 3, so that it will be out of the way when the surgeon is using instruments in the speculum.

The manner of mounting the telescope or viewing device consists of an arm 31 having a flat disk-like enlargement 32 upon one end that is seated upon the top of the disk-like flange 26 of the embossment of the bracket, and on its opposite end the arm is provided with a yoke or ring 33 that surrounds and is secured to one of the telescopic tubes 30, preferably the outer tube. The enlargement 32 of the arm is provided upon one edge with a bifurcated bearing boss 34 that projects radially from the side of the enlargement and are bored axially from the passage of the threaded portion 35 of a rod 36. The unthreaded end of the rod is bent laterally as at 37 and secured to the inner tube of the telescope through an elongated slot 38 made in the underneath portion of the outer tube. A nut 39, having a knurled or roughened outer surface, is mounted on the threaded portion 35 of the rod 36 and is guided in the bearings formed by the ears of the boss 34.

The rotation of the nut in one direction or the other will move the inner tube of the telescope axially or longitudinally with respect to the stationary telescope tube, thus focusing the lenses. It will be seen the nut is at a convenient location so that the operator, when grasping the handle by the fingers, may rotate the nut by the thumb without releasing the grip upon the handle.

In order to permit the telescope to be swung around to the dotted-line position, (Figure 2) the arm 31 is swingingly mounted upon the bracket 23. This mounting is accomplished by providing a small vertical spindle 40 that projects down from the center of the enlargement 32 of the arm, which spindle enters the reduced bore 28 of the bracket and projects down into the enlarged bore 27 near the bottom thereof. A coiled expansion spring 41 surrounds the lower portion of the spindle between the shoulder or abutment 29 and a washer or disk 42 that is secured upon the end of the spindle by means of a screw or pin 43. The diameter of the washer 42 is such that it snugly fits the enlarged bore 27 thereby affording a lower bearing for the spindle to prevent lateral or sidewise movement of the latter.

A small semi-spherical boss 44 is made on the lower face of the enlargement 32 of the arm and a correspondingly shaped depression or dent 45 is made in adjacent upper face

of the flange 26 of the bracket. This boss and dent are in such location that when these parts are interfitted they will maintain the telescope in alinement with the axis of the 5 speculum 15. When, however, it is desired to move the telescope out of range, so that the surgeon may insert instruments into the speculum, the telescope and arm are swung or moved laterally in a horizontal plane, thus 10 causing the boss 44 to leave the dent and move upon the upper face of the flange 26, such movement being accommodated by the spring 41 which allows the spindle to move longitudinally in its bearing.

15 From the foregoing it will be seen the surgeon may clamp the desired speculum in the split band 18 and raise the lamp to the proper position to illuminate the interior of the cavity under inspection and then adjust the telescope to suit his sight for viewing said area therethrough. It will be understood that the lamp has its exterior surface, excepting the 20 lenticular portion, blackened or opaque so that the light rays will be projected only in a direction into the speculum and not into the eyes of the operator. When the surgeon is ready to operate or treat the area in the cavity, the telescope may be swung with its arm into a lateral position as shown in Figures 2 25 and 3 and the lamp may be lowered slightly to be out of range of the instruments that are inserted in the speculum but at the same time illuminating the area upon which the operation or treatment is being performed.

30 35 The telescope is readily removable from the handle or support and the speculum and its mounting may also be readily removed for cleaning and sterilization.

The drawing and the within description are 40 given for the purpose of clearness of understanding only and no unnecessary limitations are to be understood therefrom, but the appended claims are to be construed as broadly as permissible in view of the prior art.

45 What I claim is:—

1. A device of the kind described comprising a support, a tool extending laterally from an end thereof, a lamp coacting with said tool and support, a bracket carried by said support, an arm mounted on and extending from 50 said bracket and capable of swinging movement independent thereof, a telescope supported by said swinging arm and normally alined with the axis of said tool, spaced ears on said arm, a rod having a threaded portion that enters said ears and has its opposite end connected to said telescope, and a nut on the rod between said ears, whereby the rotation of said nut moves the rod longitudinally to 55 adjust and focus said telescope.

60 65 2. A device of the kind described comprising a hollow handle, a removable tool extending laterally from an end thereof, a lamp at said handle end, means for moving the lamp into and out of axial alinement with said

tool, a bracket having spring arms for removably engaging said handle adjacent said lamp, an arm pivoted on said bracket and capable of horizontal swinging movement, a telescope carried by said bracket, a bearing boss on said 70 arm, a threaded rod connected to said telescope and extending through said boss, and a nut on the threaded portion of the rod and engaged with said boss, whereby rotation of said nut moves said rod longitudinally to 75 focus said telescope.

Signed at Chicago, in the county of Cook, and State of Illinois, this 6th day of March, 1931.
